(57) **CLAIM**

I claim a theft resistant support having an adjustable length tree encircling band and a clamping block, as shown and described.

DESCRIPTION

FIG. 1 is a perspective view of a theft resistant support having an adjustable length tree encircling band and clamping block showing my new design;

FIG. 2 is a front elevational view thereof;

FIG. 3 is a right side elevational view thereof;

FIG. 4 is a left side elevational view thereof;

FIG. 5 is a rear elevational view bottom view plan thereof; and,

FIG. 6 is a top plan view thereof, it being understood that a bottom plan view thereof is substantially identical hereto, but a mirror image reversal thereof.

1 Claim, 3 Drawing Sheets
